UNITED STATES PATENT OFFICE.

FRIEDRICH C. BECK, OF WINTERTHUR, SWITZERLAND.

SYRINGE FOR HYGIENIC PURPOSES.

Application filed September 2, 1921. Serial No. 498,016.

To all whom it may concern:

Be it known that I, FRIEDRICH C. BECK, a citizen of the Republic of Switzerland, and resident of Winterthur, in the Canton 5 of Zurich, Switzerland, have invented certain new and useful Improvements in Syringes for Hygienic Purposes, of which the following is a specification.

This invention is for improvements in 10 syringes for hygienic purposes having a shut-off receptacle or container for the syringing liquid in combination with a pumping device, and tubing connecting the receptacle with the pump and an injecting member. The purpose of this improved syringe 15 is to cause the cleansing liquid, by the action of the pump, to be pumped and made to circulate from the liquid container to the place of injection and thence back again 20 through a tube to the container, in such a manner, that a soiling, that is a wetting of the surroundings either before or during or after the syringing operation is prevented.

The two constructions according to my 25 invention also possess the advantage that the utilized and returning liquid, owing to the downward pressure caused by the pumping action in the receptacle or container, is sucked off into a separate compartment and 30 thus prevented from mixing with the unused liquid. Furthermore, by means of this improved device it is possible, in connection with the cleansing operation by the liquid, also to pump air to the wound to be syringed 35 in order to subsequently draw off even the last remains of the liquid from the receptacle and thereby prevent wetting of the surroundings after the use of the apparatus.

The syringe may be employed in connection 40 with any suitable receptacle, preferably with a flask or bottle of the known type, whereby a flowing out of the syringing liquid can only take place under the action of the pump.

45 In order that this invention may be clearly understood reference is made to the accompanying drawings, in which:—

Fig. 1 illustrates one form of construction 50 of the syringe and dependent parts in diagrammatical form only;

Fig. 2 shows a section, partly in elevation, of a second form of construction.

Similar parts are designated by like references throughout the several views and 55 the following specification.

Referring to Fig. 1, 1 represents a liquid container or receptacle which is air-tight with the exception of two openings, as at 1^a and 1^b, serving for the connection therewith of rubber or the like tubes. One of these 60 openings, namely that at 1^a, is connected and communicates with the tube 3^a of a pumping device, for instance a clyster-pump 2 fitted with the usual valves as at 2^a and 2^b respectively, the end 3^c of the tube 3^a 65 containing the valve 2^b and carrying a member 4 adapted to be inserted into the wound to be syringed. Fixed over the other opening 1^b and communicating therewith is a rubber or the like tube 5 which is in turn 70 connected to and communicates with the end 3^c. The valve 2^b is hereby so disposed that when opened under the pressure of the liquid coming from the pump 2 it closes the tube 5 while, when the pump is not in action, the said valve 2^b returns into the position illustrated.

In operation the device described acts as follows: Subsequent to the filling of the receptacle 1 with the syringing liquid and the 80 fitting in position of the pump 2 and tubes 3^a, 3^c and 5, the user applies the member 4 to the wound. The pump is then actuated in the manner known, the air primarily being forced from the pump to the wound while 85 the liquid is simultaneously sucked from the receptacle. The result is that a rarefaction of the air in the receptacle takes place which, however, is neutralized by the sucking off from the wound of the air by the tube 5. Further action of the pump now causes 90 liquid to be forced into the wound and more liquid to be sucked from the receptacle. Again there is rarefied air produced in the receptacle but, owing to the suction of liquid 95 from the wound neutralized by the tube 5. This process may then be repeated at will. The pump 2 forms with the tube parts 3^a and 3^c the supply and the end 3^c alternately 100 forms a channel for the supply and the return to the receptacle of the liquid.

In the second form of construction, Fig. 2, I again provide a liquid container 1 which now has the form of a flask or bottle of the well known type and constructed of two walls with an air-tight chamber between the same, the said bottle being mounted in and protected by a casing 1^c. The neck-portion 1^b of the casing is screw-threaded to receive the correspondingly 110

screw-threaded end 3^a of the pipe 3^a, a rubber washer 9 rendering the connection between the bottle 1 and the pipe or tube 3^a air-tight. The other end of the latter has 5 screwed thereon a cover 10 adapted to receive a rotatable disc 11. This disc is internally screw-threaded and serves for the reception of a correspondingly screw-threaded tubular member 12 having a flange 10 12^a which, in turn, carries a pin 13. Abutting against the flange 12^a and fixed in the pipe 3^a is a plate 14 provided, firstly, with a central bore to receive a pipe 15 mounted concentrically within the pipe 3^a and extending 15 to near the top of the bottle, and secondly, with a series of openings, as at 16, with one of which openings the aforesaid pin 13 engages. Connected with the tubular member 12 is a tube 3 forming part 20 of the clyster-pump 2 fitted with valves 2^a and 2^b, the continuation of the tube 3 and pump 2 being the clyster-pipe or tube 3^c which, like the tube or return-pipe 5 extends through and carries the member 4 to 25 be inserted into the wound. The return pipe 5 is hereby made to project through the wall of the pipe 3^a whence it follows the course of the adjacent pipe 15.

Part of the device described, namely the 30 cover 10 with disc 11, tubular sleeve 12 and plate 14 is not essential and may therefore be omitted.

The action of the device as last described and when in use is as follows:

35 Upon the filling of the bottle 1 with syringing liquid the pipes 5 and 15 are inserted into the bottle and air-tight connection of the latter with the pipe 3^a effected. Thereafter the whole is turned upside down 40 into the position illustrated in Fig. 2, the liquid thus descending into the pipe 3^a while an air space is produced at the now top of the bottle 1. The member 4 is then inserted into the wound and the disc 11 turned. Since the pin 13 prevents the tubular member 12 from following such movement, the said tubular and screw-threaded member is caused to rise thereby allowing the liquid to penetrate through the openings 16, previously covered by the flange 12^a, into the tube 45 50 55 60 65 70 75 80 85 90 95 100 105 110 115 120 125 130

3. If now the pump 2 is put in action the liquid is sucked through the clyster-pipe 3^c and forced into the wound to be syringed. And owing to this sucking action a space rarefied of air is again produced in the bottle 1, which rarefaction, however, is neutralized by the return tube 5. That is to say, the liquid injected is immediately sucked back into the bottle. When it is desired to stop the syringing operation, the disc 11 is turned back until the flange 12^a of the tubular member 12 is again made to rest upon the plate 14, as illustrated, thereby closing the openings 16. Further actuation of the pump 2 results in air being

sucked through the pipe 15 into the wound, which air is again sucked back through the tube 5 thereby carrying with it any remains of the utilized liquid.

It will be understood that the pumping device, instead of being arranged between the supply tubes 3^a and 3^c, could also be fitted in the return pipe or tube 5. Furthermore, the clyster-pump 2 may be replaced by any other pumping means, while the construction and arrangement of other parts constituting the syringe might be made subject to many other modifications without altering the character of the invention.

Having thus fully described my said invention what I claim and desire to secure by Letters Patent is:—

1. A syringe for hygienic purposes comprising in combination a closed fluid reservoir of rigid construction having inlet and outlet ports, suctional means for withdrawing the liquid through the outlet port whereby a partial vacuum is created in the reservoir, and means for returning the fluid to the reservoir through the inlet port under the influence of the said vacuum.

2. A syringe for hygienic purposes comprising in combination a closed fluid reservoir of rigid construction having inlet and outlet ports, said inlet port being substantially above said outlet port when the reservoir is in operative position, a tube in connection with the said outlet port, a pump in connection with the said tube whereby the fluid is withdrawn and a partial vacuum created in the reservoir, and a tube in connection with the said inlet port whereby the fluid is returned to the reservoir under influence of the said vacuum.

3. A syringe for hygienic purposes comprising in combination a fluid reservoir in the shape of an inverted bottle, a tube in connection with the mouth of the reservoir, another tube extending through the mouth of the reservoir, suctional means for withdrawing the fluid through one of the said tubes and thereby creating a partial vacuum in the reservoir, and means for returning the fluid to the reservoir under the influence of the said vacuum.

4. A syringe for hygienic purposes comprising in combination a fluid reservoir consisting of an inverted double-walled bottle, a U-shaped outlet tube having one of its arms in connection with the mouth of the reservoir, an inlet tube passing through the wall of said U-shaped tube and extending upwardly through the mouth and substantially to the top wall of the reservoir, a pump in connection with the other arm of the U-shaped tube whereby the fluid is withdrawn and a partial vacuum created in the reservoir, and means for returning the fluid to the reservoir through said inlet tube under the influence of the said vacuum.

5. In a syringe for hygienic purposes, the combination, with a member adapted to be inserted into the wound to be syringed, and a liquid container in the form of a bottle, 5 of a pipe of approximately U-shape tightly joined with its one end to the neck of the bottle and making communication therewith, two smaller pipes mounted approximately concentrically within the bottle and 10 reaching with one end to near the bottle top, one of the said smaller pipes following the bend of the U-pipe and the other small pipe projecting through the bottom of the said bend and also extending through the 15 inserting member with which it is rigidly connected; a pumping device, a supply tube forming part of the pumping device and being in communication with the small pipe extending through the said U-bend on the 20 one hand and extending through the inserting member on the other hand, and means to cause the syringing liquid to circulate from the bottle to the wound to be syringed and thence back to the bottle when the 25 pumping device is actuated.

6. In a syringe for hygienic purposes, the combination, with a member adapted to be inserted into the wound to be syringed, and

a bottle containing the syringing liquid, of a housing for the bottle, a pipe of approximately U-shape detachably fitted to the housing and communicating with the bottle, means to effect a tight connection between the bottle and the U-pipe, a plate fixed in the free end of said U-pipe and having a central bore and a series of perforations, a sleeve adjacent to the said plate and provided with a flange which covers the said perforations, means to adjust the sleeve vertically, a pumping device, a supply tube 40 forming part of the pumping device and being connected with the said sleeve on the one hand and extending through the inserting member on the other hand, and means to cause the syringing liquid to circulate from the bottle to the wound to be syringed and thence back to the bottle when the pumping device is actuated.

In testimony whereof I have hereunto set my hand in the presence of two subscribing 45 witnesses.

FRIEDRICH C. BECK.
